UNITED STATES PATENT OFFICE.

ROSCOE P. TIMSON, OF LYNN, AND GEORGE NORMAN ALBREE, OF SWAMPSCOTT,
MASSACHUSETTS; SAID TIMSON ASSIGNOR TO SAID ALBREE.

AEROPLANE.

1,179,978.

Specification of Letters Patent. Patented Apr. 18, 1916.

Application filed May 31, 1912, Serial No. 700,879. Renewed March 11, 1916. Serial No. 83,689.

To all whom it may concern:

Be it known that we, ROSCOE P. TIMSON and GEORGE NORMAN ALBREE, both citizens of the United States, and residents of Lynn and Swampscott, respectively, in the county of Essex and State of Massachusetts, have invented new and useful Improvements in Aeroplanes, of which the following is a specification.

10 This invention relates to aeroplanes, and has for its object the provision of a plane-supported structure characterized by inherently stable equilibrium, which will automatically restore itself to a condition of even balance, whether disturbed temporarily either longitudinally or laterally, and which is therefore adapted to be safely sustained and guided in the air provided it is equipped with the usual propulsive machinery.

20 In order to set forth the principles of this invention, the machine herein described will be considered both in its simple aspect as a gliding or soaring machine, and in its completer aspect as a propelled flying machine.

25 In the drawings hereto annexed, which illustrate an example of the invention—Figure 1 is a diagram to explain the characteristic principle of longitudinal equilibrium; Fig. 2 is a diagram to explain the principle of lateral equilibrium, or automatic self-banking; Fig. 3 is a front elevation showing the preferred form of machine; Fig. 4 is a plan view of the machine; and Fig. 5 is a side elevation of the machine.

35 Referring to Fig. 1: P represents the supporting planes, H the backbone or framework, extending fore and aft on the line 1—1, T the tail, and W a preponderant weight; these elements being so arranged that the center of gravity of the whole structure falls well forward of the center of supporting air pressure. By repeated experiment, it has been demonstrated that the center of gravity *cg* should lie about half way between the center of supporting pressure *cp* and the front edge of the supporting plane P, provided this edge be at right angles to the center line 1—1 of the machine.

40 The tail T, which balances and controls the flight of the structure is so inclined that forward movement through the air produces always a downward air pressure on the tail, or, in other words, the plane of the tail lies

55 at an angle with the plane of support, an angle which opens forward, as referred to the direction of movement of the machine. Thus the tendency of the weight W is to depress the front of the machine, while that of the tail is to depress the rear of the machine. 60 The center of pressure *cp* constitutes the fulcrum to which the dynamic moments of the opposing efforts are referred. Suppose a gliding machine to be built according to the principles above explained, the tail T 65 set at a fixed angle with the body B, and therefore with the planes P (Fig. 1), and that this glider is simply released in the air at a height from the ground. The tail T then exerts no depressing effect but the 70 weight W depresses the head of the glider which falls downward and forward; the air pressure on the upper surface of the tail due to the flight increases with the speed of the glider, and depresses the rear of the machine more and more, until the glider assumes a nearly horizontal position, in which it will glide forward and downward in a straight course. If, instead of being 75 simply released in the air, the machine be given a forward initial impetus, it will incline upward after release under impulse, and then incline and glide forward and downward.

80 It will be clear that if the tail T were set 85 in a greater angle with the center line of the glider, its righting effect would be more quickly asserted and that also its effect to check the speed of the machine would be the greater, that with the tail set at a slight 90 angle the effect would be a swift long glide, while with the tail set at a wider angle the effect would be a slow and short distance glide. It will also be clear that if the tail T were set at a reverse angle, be it ever so 95 slight, its effect would be to lift the rear of the machine, supplementing instead of opposing the moment of the weight W, and that the machine would turn completely over, and glide, if at all, bottom up. This 100 may easily be tested by launching a glider, constructed as above described, bottom up. It will instantly turn over, and glide to earth right side up.

105 Further to illustrate the principle of balance and equilibrium of such a machine as is herein illustrated, suppose the weight W to be transformed into a motor and propeller

of such proportions that with the motor and the aviator in the machine the static balance of the machine remains as before. With the tail T set a proper angle, assume the machine to be in flight at such a rate that the air, pressing on the upper surface of the tail T holds the machine tilted slightly upward, so that as a whole it travels forward at unchanging elevation. Now suppose the 10 motor speed to be increased; increased speed results, and with it increased pressure on the upper surface of the tail T, which tilts the head of the machine upward until uniform progress forward and upward is attained. Should the motor be slowed down, or even stopped, on the other hand, with decrease in speed of forward motion there must come decrease in downward pressure on the tail T, and then the machine will 15 move downward at an angle and velocity determined by the several factors. The effects of a governable tail T will now become apparent. Increase of its angular set, to augment the air pressure on its surface, will 20 tilt the machine upward, and decrease its rate of progress, and vice-versa. To descend to earth, the motor should be stopped and the tail-angle increased to a practicable maximum, so as to effect a slow 25 downward glide. In this manner the described relationship of the weight, tail and center of supporting pressure on the supporting plane insures automatic balance 30 in the direction of flight, or in other words, automatically takes care of longitudinal 35 equilibrium.

Referring now to Fig. 2, which shows in diagram the machine coming "head on," and tilted sidewise, as it might be by a gust 40 of wind: The weight of the machine pulls it vertically downward, as at cg , the supporting air pressure holds it up, as indicated by the vertical component $c'p'$, and at the same time there will be a tendency to 45 slide laterally and downwardly. As the tail T is tilted sidewise, the downward pressure of the air will be exerted at an angle to the vertical, as on the line tp , producing a horizontal component sp , which, acting at the 50 tail T, slew the tail sidewise, in the direction of the arrow at sp , turning the head of the machine toward the side on which it is depressed and causing the machine momentarily to make a curved flight; the centrifugal force developed by curvilinear movement overcomes the tendency to lateral and downward side slip and at the same time the righting moment, due to the shifting 55 of the center of gravity outward, that is to say, away from the depressed side of the machine, draws the elevated wing down and brings the machine back to an even keel, and perhaps inclines it in the other direction, so that straight line of flight is resumed after a short period of sinusus flight.

This automatic righting action resembles that of a moving bicycle in its instantaneous restoration of the machine to its normal level whenever it is momentarily deflected or inclined.

In the preferred construction illustrated in Figs. 3, 4 and 5, the supporting planes are arched, each wing being composed of upwardly extending sections P' , downwardly extending sections P^2 , and upturned tips P^3 . This arched construction produces regions of high air density near the crown of the arch, lends itself readily to stiffening by means of truss rods or tie-wires, and reduces the liability to side-sliding. The behavior 80 of gliding models built on this plan shows that whenever one wing is depressed the machine automatically banks itself and resumes horizontal position.

It will now be clear that a machine of the 85 character described may be steered without any vertical rudder, by means of horizontal rudders, such as P^4 (Fig. 4) which are hinged to turn on axis transverse to the fore-and-aft center line of the machine, or 90 by wing-warping devices. By including horizontal rudders or warping wings, the machine may be inclined to one side or the other, and then the tail, acting as above described, will swing the machine in a 95 curve with its center on the depressed side.

A continuously self-sustaining machine embodying the principles above explained, is suggested by Figs. 3, 4 and 5. The weight of the entire body structure, including engine E, housing H, propellers B, frame F and pontoons C is so distributed that the center of gravity is located at cg (Fig. 5). The aviator's seat A is so placed that his weight shall not appreciably shift the center of gravity of the whole. The wings are arched, and comprise planes P' , P^2 and P^3 , and horizontal rudders P^4 which are hinged on the transverse line p^4 . The tail T is pivoted at t , and controlled by the aviator 110 through connections which include toggles T', and stops S, S' limit the extremes of inclination of the tail T. A vertical rudder R may be provided, but is not essential; it may well be set at a slight angle to compensate for drift due to propeller torque, if but one propeller is employed. The machine shown is adapted to rise from and alight on water; the usual landing wheels and a suitable chassis may be substituted for 115 the pontoons C.

In the preferred construction illustrated in Figs. 3, 4 and 5, the propeller shaft, and therefore the line of forward draft, is parallel to the supporting planes, and these 125 planes are made as straight, from front to rear, as the necessities of construction will allow. The under surfaces of the supporting wings are those which should be flat or straight from front to rear. The tail plane, 130

as shown, should be flat on its upper side, and have its leading edge close to the trailing edge of the supporting planes.

As was demonstrated at a relatively early date by the performance of Lilienthal and Pilcher (among others) supporting surfaces arched from front to rear, while affording increased lift, naturally tended to make the machine move in a curve coincident with the curvature of the supporting surfaces, and therefore to plunge downward. The center of gravity, in such machines, necessarily had to be located in the rear of the actual center of upward pressure, and with the weight so disposed, a tail plane, set at or moved to, a negative angle, sufficed or assisted to prevent the machine from diving in response to the tendency of the curved wing surfaces to follow the path of their own curvature. If the center of gravity in a machine having a curved supporting surface, be placed forward, or even coincident with, the center of supporting pressure, the diving tendency will be too strong to be overcome by a tail plane set at a negative angle less than that which will unduly retard the gliding movement.

The stops S, S' are so fixed that the upper stop prevents the tail plane from reaching a position parallel with the supporting planes, and so that the lower stop will fix the tail plane at the extreme inclination suited to a slow downward glide. It is important to so limit the adjustment of the tail plane that under no conditions can the balancing downward pressure of air on its upper surface be lost.

It is well known that the center of supporting pressure varies its position with the angle of positive inclination, and with speed advance, so that the positions of center of gravity and center of pressure, shown in the drawings are intended solely as diagrammatic indications. The constructor will take into account the known data with respect to changes of center of pressure and proportion the machine so that the center of gravity will be forward of the center of pressure under any conditions.

What we claim and desire to secure by Letters Patent is:

1. In an aeroplane, the combination of supporting planes, a body, and a tail plane, all so coördinated that the center of gravity of the structure is located forward of the center of pressure of the supporting planes, and the tail plane presents its upper surface at an angle to normally exert during flight a downward air pressure pull in opposition to the downward pull of the weight of the structure, referred to the center of pressure as a fulcrum, and a support for the aviator substantially coincident with the center of gravity of the structure.

2. In an aeroplane, the combination of

laterally arched supporting planes, a body, and a tail plane, all so coördinated that the center of gravity of the structure is located forward of the center of pressure of the arched supporting planes, and the tail plane presents its upper surface at an angle to normally exert during flight a downward air pressure pull in opposition to the downward pull of the weight of the structure, referred to the center of pressure as a fulcrum, and a support for the aviator substantially coincident with the center of gravity of the structure.

3. In an aeroplane, the combination of supporting planes, a body, and a tail plane, all so coördinated that the center of gravity of the structure is located forward of the center of pressure of the supporting planes, and the tail plane presents its upper surface at an angle to normally exert during flight a downward air pressure pull in opposition to the downward pull of the weight of the structure, referred to the center of pressure as a fulcrum, means such as horizontal rudders for laterally inclining the aeroplane from its normal horizontal position, and a support for the aviator substantially coincident with the center of gravity of the structure.

4. In an aeroplane, the combination of laterally arched supporting planes, a body, and a tail plane, all so coördinated that the center of gravity of the structure is located forward of the center of pressure of the arched supporting planes, and the tail plane presents its upper surface at an angle to normally exert during flight a downward air pressure pull in opposition to the downward pull of the weight of the structure, referred to the center of pressure as a fulcrum, means such as horizontal rudders, for laterally inclining the aeroplane from its normal horizontal position, and a support for the aviator substantially coincident with the center of gravity of the structure.

5. In an aeroplane, the combination of supporting planes substantially flat in fore-and-aft section, a body, and a tail plane, all so coördinated that the center of gravity of the structure is located forward of the center of pressure of the supporting planes, and the tail plane presents its upper surface at an angle to normally exert a downward pull in opposition to the downward pull of the weight of the structure, referred to the center of pressure as a fulcrum, and a support for the aviator substantially coincident with the center of gravity of the structure.

6. In an aeroplane, the combination of laterally arched supporting planes substantially flat in fore-and-aft section, a body, and a tail plane, all so coördinated that the center of gravity of the structure is located forward of the center of pressure of the supporting planes, and the tail plane pre-

sents its upper surface at an angle to normally exert a downward pull in opposition to the downward pull of the weight of the structure, referred to the center of pressure as a fulcrum, and a support for the aviator substantially coincident with the center of gravity of the structure.

7. In an aeroplane, the combination of supporting planes, a body, and a tail plane, all so coördinated that the center of gravity of the structure is located forward of the center of pressure of the supporting planes, and the tail plane presents its upper surface at an angle to normally exert during flight a downward air pressure pull in opposition to the downward pull of the weight of the structure, referred to the center of pressure as a fulcrum, a propeller having its line of draft substantially parallel to the fore-and-aft section of the supporting planes, and a support for the aviator substantially coincident with the center of gravity of the structure.

8. In an aeroplane, the combination of laterally arched supporting planes, a body, and a tail plane, all so coördinated that the center of gravity of the structure is located forward of the center of pressure of the supporting planes, and the tail plane presents its upper surface at an angle to normally exert during flight a downward air pressure pull in opposition to the downward pull of the weight of the structure, referred to the center of pressure as a fulcrum, a propeller having its line of draft substantially parallel to the fore-and-aft section of the supporting planes, and a support for the aviator substantially coincident with the center of gravity of the structure.

9. In an aeroplane, the combination of supporting planes, a body, and a tail plane, all so coördinated that the center of gravity of the structure is located forward of the center of the supporting planes, and the tail plane presents its upper surface at an angle to normally exert during flight a downward air pressure pull in opposition to the downward pull of the weight of the structure, referred to the center of pressure as a fulcrum, means such as horizontal rudders for laterally inclining the aeroplane from its normal horizontal position, a propeller having its line of draft substantially parallel to the fore-and-aft section of the supporting planes, and a support for the aviator substantially coincident with the center of gravity of the structure.

10. In an aeroplane, the combination of

laterally arched supporting planes, a body, and a tail plane, all so coördinated that the center of gravity of the structure is located forward of the center of pressure of the arched supporting planes, and the tail presents its upper surface at an angle to normally exert during flight a downward air pressure pull in opposition to the downward pull of the weight of the structure, referred to the center of pressure as a fulcrum, means such as horizontal rudders, for laterally inclining the aeroplane from its normal horizontal position, a propeller having its line of draft substantially parallel to the fore-and-aft section of the supporting planes, and a support for the aviator substantially coincident with the center of gravity of the structure.

11. In an aeroplane, the combination of supporting planes substantially flat in fore-and-aft section, a body, and a tail plane, all so coördinated that the center of gravity of the structure is located forward of the center of pressure of the supporting planes, and the tail plane presents its upper surface at an angle to normally exert a downward pull in opposition to the downward pull of the weight of the structure, referred to the center of pressure as a fulcrum, a propeller having its line of draft substantially parallel to the fore-and-aft section of the supporting planes, and a support for the aviator substantially coincident with the center of gravity of the structure.

12. In an aeroplane, the combination of laterally arched supporting planes substantially flat in fore-and-aft section, a body, and a tail plane, all so coördinated that the center of gravity of the structure is located forward of the center of pressure of the supporting planes, and the tail plane presents its upper surface at an angle to normally exert a downward pull in opposition to the downward pull of the weight of the structure, referred to the center of pressure as a fulcrum, a propeller having its line of draft substantially parallel to the fore-and-aft section of the supporting planes, and a support for the aviator substantially coincident with the center of gravity of the structure.

Signed by us at Boston, Massachusetts, this 25th day of May 1912.
